(57) **CLAIM**

(**) Term: **14 Years**

The ornamental design for a portion of all terrain vehicle body and seat, as shown and described.

(21) Appl. No.: **29/158,831**

DESCRIPTION

(22) Filed: **Feb. 26, 2002**

FIG. 1 is a top plan view of a portion of an all terrain vehicle body and seat according to a preferred embodiment of the present invention;

(51) LOC (7) Cl. **12-11**

FIG. 2 is a left side view thereof; and,

(52) U.S. Cl. **D12/107; D6/354**

FIG. 3 is a right side view thereof.

(58) Field of Search D12/87, 107, 180/225,

The portions of the claimed all terrain vehicle which are not

180/229, 223, 247, 291, 292, 311, 312,

315; D6/354; 297/195.1, 195.11, 201-205,

217.1

represent the boundaries of the claimed design while the

other broken lines which show environment or structure are

for illustrative purposes only; the broken lines form no part

of the claimed design.
